UNITED STATES PATENT OFFICE.

WILLIAM H. FAUBER, OF CHICAGO, ILLINOIS.

DESIGN FOR A SPROCKET-WHEEL.

SPECIFICATION forming part of Design No. 29,827, dated December 20, 1898.

Application filed November 26, 1898. Serial No. 697,566. Term of patent 7 years.

To all whom it may concern:

Be it known that I, WILLIAM H. FAUBER, a citizen of the United States, residing in the city of Chicago, county of Cook, and State of Illinois, have invented and produced a new and original Design for Sprocket-Wheels for Velocipedes, of which the following is a specification, reference being had to the accompanying drawing, forming a part thereof.

10 Said drawing illustrates in side elevation a sprocket-wheel made in accordance with my novel design.

The essential or characteristic features of a sprocket-wheel made in accordance with 15 my design consists of an outer circular rim having on its periphery a plurality of openly-spaced radial projections or sprocket-teeth, an inner ring or hub concentric with said rim, and a plurality of spokes or arms extending

20 generally in a radial direction between said hub and rim. Said spokes are five in number and are spaced at equal distances about the hub. They are made solid at their inner ends, or at their points of connection with the hub, and are divided or branched at their outer end from a point about midway between the rim and hub, said branched end portions being divergent and curved reversely to each other and joined to the rim at circumferentially 25 separate points. The proximate curves of said divergent end portions of each spoke are symmetrically disposed with reference to a radial line passing centrally through the spoke, to which curves said line is tangential.

30 Said spokes are widest in their parts a short distance from the inner ring or hub, and such widest parts are bounded by oppositely-arranged convexly-curved lines, which merge at their outer ends into the reverse inner 35 curves of the divergent end portions of the

arms. Each spoke is provided on each side thereof immediately adjacent to said ring and inside of said widest part with oppositely-arranged concave notches or recesses, and the proximate parts of said concave notches of 45 adjacent spokes are joined by straight lines, which form portions of the periphery of said inner ring or hub and which give to said ring the general shape of a decagon, with the spokes joined to alternate sides thereof. The 50 inner ends of the convexly-curved lines bounding the widest parts of the spokes are joined to the outer parts of said concave notches or recesses at the base of the spokes by short straight and oblique or inwardly-divergent 55 lines, which provide on opposite sides of said spokes just outside of said concave notches oppositely-located and oppositely-directed sharp-pointed spurs or projections. Each of said spokes is provided in its widest part with 60 a central opening having the form of a trapezium. Upon the inner circumference of said rim, midway between each two adjacent spokes, are inwardly-projecting pointed spurs, the margins of which are joined to the inner 65 curves of the divergent end portions of the spokes by concave curved lines. Said rim is provided opposite to said projections with circular openings.

I claim as my design—

The design for a sprocket-wheel for bicycles substantially as herein shown and described.

Dated this 23d day of November, A.D. 1898, at Chicago, Illinois.

WILLIAM H. FAUBER.
